UNITED STATES PATENT OFFICE.

PAUL GIBSON BLANFORD, OF PORTSMOUTH, VIRGINIA.

DESIGN FOR A BADGE.

No. 38,010.

Specification for Design.

Patented May 15, 1906.

Application filed April 4, 1906. Serial No. 309,944. Term of patent 3½ years.

To all whom it may concern:

Be it known that I, PAUL GIBSON BLANFORD, a citizen of the United States, residing at Portsmouth, in the county of Norfolk and State of Virginia, have invented a new, original, and ornamental Design for Badges, of which the following is a specification, reference being had to the accompanying drawing, forming a part thereof, in which the figure is a plan view of a badge, showing my new design.

In the center is shown a bust of the noted explorer and discoverer, Captain John Smith. Immediately above this bust is shown the head of an American Indian, on either side of which is represented a wigwam, these features of the badge being separated from the head of Smith by a circular line. Above the head of Smith, and to the left and right thereof, respectively, are representations of the "Monitor" and the "Merrimac." Below the bust of Smith is a representation of the United States Capitol building, which is separated from said bust by means of a circular line. Below said bust and at the right

and left thereof, respectively, are represented a modern battle ship and a cannon. To the left of the bust of Smith is represented the remains of the old church at Jamestown, with landscape and scenic accessories, such representation being separated from the adjacent representations of the "Monitor" and the cannon by a circular line. To the right of the bust is a representation of a shield which is separated from the adjacent representation of the "Merrimac" and of the modern war vessel by a circular line. The various representations on the badge are confined within a circle, between which circle and the periphery of the badge appear, at the top, "Jamestown Exposition Norfolk 1907" and at the bottom the dates "1607 1907."

I claim—

The ornamental design for a badge as shown.

PAUL GIBSON BLANFORD.
